[57] CLAIM

The ornamental design for a luggage handling hand cart
with inlay pattern side panels and top, shown and de-
scribed.

DESCRIPTION

FIG. 1 is a perspective view of our luggage handling
hand cart with inlay pattern side panels and top;
FIG. 2 is an end elevational view, the opposite end view
being identical;

FIG. 3 is a side elevational view, the opposite side ele-
vational view being identical; and,
FIG. 4 is a top plan view thereof.

FIG. I

FIG.2
